UNITED STATES PATENT OFFICE

2,447,904

HOSE SUPPORTER

Simon J. Falsey, New Haven, Conn.

Application June 30, 1945, Serial No. 602,571

4 Claims. (Cl. 24—263)

1

The present invention relates to a hose supporter, and has for an object to provide a supporter which may be engaged and disengaged with the stocking and disengaged therefrom with facility, and without injurious pulling upon or distortion of the stocking, and which when in place will be extremely flat and therefore not produce any appreciable bulge.

A further object is to provide a hose supporter constructed of two cooperative interlocking wedge parts and a fabric tape member, the two interlocking parts consisting of a pocket wedge member and an insert wedge member having downwardly converging wedge surfaces.

It is further proposed to provide a hose supporter wherein the cooperating wedge members are maintained in wedging engagement through the upward pull of the tape, so that increased pull on the tape causes the wedge members to be more firmly interlocked. According to the invention the pull of the tape is in an upward direction, while the engaging direction of the insert wedge member with the pocket wedge member is in a downward direction, and it is a further object of the invention to provide a novel arrangement of slot means in the pocket member, by means of which the tape may be threaded therethrough and connected to the insert wedge member in such relation that upward pull upon the tape exerts downward pull upon the insert wedge member.

With the above and other objects in view, an embodiment of the invention is shown in the accompanying drawings, and this embodiment will be hereinafter more fully described with reference thereto, and the invention will be finally pointed out in the claims.

In the drawings:

Fig. 1 is a front elevation of a hose supporter, according to the exemplary illustrated embodiment of the invention, and showing the same in its operative position attached to a stocking top.

Fig. 2 is an isometric perspective view of the hose supporter showing the insert wedge member in disengaged relation with respect to the pocket wedge member.

Fig. 3 is an isometric perspective view showing the engaged relation of the insert wedge member with the pocket wedge member.

Fig. 4 is a horizontal sectional view, taken along the line 4—4 of Fig. 1.

Fig. 5 is a vertical sectional view, showing the stocking top engaged over the pocket wedge member and the insert wedge member in separated relation about to be engaged therewith.

2

Fig. 6 is a similar view, showing the insert wedge member engaged with the pocket wedge member, with the stocking interposed and before forcing the insert wedge member downwardly into interlocking engagement.

Fig. 7 is a similar view, showing the insert wedge member in operative interlocked relation with the pocket wedge member, with the stocking top interposed, the arrows indicating the line of pull of the tape with respect to the pocket wedge member.

Similar reference characters indicate corresponding parts throughout the several figures of the drawings.

Referring to the drawings, the hose supporter, according to the exemplary illustrated embodiment of the invention shown therein, comprises a pocket wedge member in the form of a base plate portion 10 provided upon its forward side with a pair of laterally spaced downwardly converging angular cross-section flange formations 11 providing undercut channel grooves 12 at each side of the base portion. The base portion extends for a substantial distance above the upper ends of the flange formations 11, and is provided with an upper horizontal slot 13 and a lower horizontal slot 14 disposed in vertically spaced parallel relation to each other.

The insert wedge member 15, which is adapted to be cooperatively engaged with the pocket wedge member, has its side edges 16 downwardly converging in substantially parallel relation to the channel grooves 12 of the pocket wedge member. The insert wedge member is provided at its upper end with a tape receiving slot 17 and a tape attaching bar portion 18 forming the upper side of the slot 17. The tape 19 is engaged about the bar portion 18 and secured by a row of stitching 20, being thereupon threaded through the lower slot 14 of the pocket wedge member from its forward to its rearward side and then carried upwardly and through the upper slot 13 from the rearward to the forward side.

The dimensions of the insert wedge member are such that when it is engaged in the pocket wedge member, with the stocking top 21 interposed, the bar portion 18 at the upper end of the insert wedge member is at a point substantially above the lower slot 14, and essentially remains above this slot in the fully engaged position of the insert wedge member. Consequently, upward pull upon the tape, which, following the fastening of the supporter, takes place between the stocking top and the garment to which the tape 19 is attached, causes the insert wedge member to

be pulled downwardly with respect to the pocket wedge member, so that a constant wedging engagement is maintained, and any increase in the pull on the tape causes the insert wedge member to be more firmly wedged into the pocket wedge member. The supporter is disengaged simply by pulling upwardly upon the upper end of the insert wedge member, causing the tape to move through the slots 13 and 14 during this disengaging movement.

I have illustrated and described a preferred and satisfactory embodiment of the invention, but it will be understood that changes may be made therein, within the spirit and scope thereof, as defined in the appended claims.

Having thus described my invention, what is claimed and desired to be secured by Letters Patent is:

1. In a garment supporter, clasp means comprising a pair of downwardly convergent wedge members each including cooperating wedge portions, the wedge portions of one member being wedgingly engageable in a downward direction with the wedge portions of the other member to interlockingly engage a portion of the garment therebetween, one of said members having a slideway, and a suspension tape member, for connection to a supporting garment spaced upwardly from the garment to be supported, and secured at its lower end to the other of said wedge members and slidably engaged between its upper and lower ends with said slideway of the first of said members, the point of securing of said tape member to said second member being above its point of sliding engagement with said slideway of the other of said members in the wedgingly engaged relation of said members, whereby upward pull on the upper end of said tape member exerts a downward pull on its lower end and a downward wedging force on the wedge member to which it is secured.

2. In a garment supporter, clasp means comprising a socket wedge member having a pair of laterally spaced downwardly converging channel grooves at its forward side and having slideway means in proximity to its upper end, an insert wedge member having downwardly converging side edges and wedgingly engageable in a downward direction with said socket wedge member with a portion of the garment therebetween, and a suspension tape member, for connection to a supporting garment spaced upwardly from the garment to be supported, secured at its lower end to the upper end of said insert wedge member and slidably engaged between its upper and lower ends with said slideway means of said socket wedge member, said point of securing of said tape to said insert wedge member being above its point of sliding engagement with said slideway means of said socket wedge member in the engaged relation of said members, whereby upward pull on the upper end of said tape member exerts a downward pull on its lower end and

a downward wedging force on said insert wedge member.

3. In a garment supporter, clasp means comprising a socket wedge member having a pair of laterally spaced downwardly converging channel grooves at its forward side and a horizontal slot in its upper end portion, an insert wedge member having downwardly converging side edges and wedgingly engageable in a downward direction with said socket wedge member with a portion of the garment therebetween, and a suspension tape member, for connection to a supporting garment spaced upwardly from the garment to be supported, secured at its lower end to the upper end of said insert wedge member and slidably engaged between its upper and lower ends through said slot of said socket wedge member, said point of securing of said tape to said insert wedge member being above its point of sliding engagement with said slot in the engaged relation of said members, whereby upward pull on the upper end of said tape member exerts a downward pull on its lower end and a downward wedging force on said insert wedge member.

4. In a garment supporter, clasp means comprising a socket wedge member having a pair of laterally spaced downwardly converging channel grooves at its forward side and a pair of vertically spaced horizontal slots in its upper end portion, an insert wedge member having downwardly converging side edges and wedgingly engageable in a downward direction with said socket wedge member with a portion of the garment therebetween, and a suspension tape member, for connection to a supporting garment spaced upwardly from the garment to be supported, secured at its lower end to the upper end of said insert wedge member and slidably engaged between its upper and lower ends from front to rear through the lower of said slots of said socket wedge member and from rear to front through the upper of said slots, said point of securing of said tape to said insert wedge member being above its point of sliding engagement with the lower of said slots in the engaged relation of said members, whereby upward pull on the upper end of said tape member exerts a downward pull on its lower end and a downward wedging force on said insert wedge member.
